POLISHING MACHINE

Ernst Faber, Stuttgart, Germany

Application May 20, 1936, Serial No. 80,872
In Germany June 4, 1935

3 Claims. (Cl. 15—49)

This invention relates to a floor and the like polishing machine driven by electric motor with a pivotally attached guiding handle and a driving pinion which is mounted on the shaft of the 5 pivotally mounted motor and is pressed by weight or spring force or both against the driving disc of the brush tool.

The invention has for its object so to modify this arrangement that the weight or spring force 10 is also utilized, while the machine is out of operation, for firmly securing the handle in its upright inoperative position, more particularly so that the machine when being put aside, when it is suitably carried by means of the handle, cannot 15 through overbalancing fall over about the pivotal point of the handle and strike the ground. Such overbalancing is particularly likely to occur, when the handle is pivoted not in a central transverse axis of the machine casing, but externally of the middle, which is of advantage, since otherwise the 20 machine is liable to have a jumping motion when in use.

According to the invention the object aimed at is realized by the provision of an extension of the 25 motor casing, which is acted on by the weight of the motor or by the spring bearing against a fixed abutment and which, when the machine is not in use, that is when the handle is upright, bears against a projection on the handle. At the same 30 time the weight or the spring presses the extension of the motor casing against the projection on the handle which through its pivotal attachment to the casing offers resistance, so that the machine can be grasped by the handle for placing it aside without it falling over in the manner 35 explained above and the coupling of motor casing extension and handle projection becoming released. Furthermore, the handle is thus secured in a reliable manner from becoming inadvertently released from its locked position through 40 shocks or the like acting on it.

The accompanying drawing illustrates a constructional example of the arrangement according to the invention in a vertical section, partly in 45 elevation.

a is the motor which is mounted so as to be capable of swinging by means of two gudgeons *b* disposed outside its centre of gravity in upper lateral wings *c* of the substantially cylindrical casing *d*. *e* is the current lead and *f* is a driving pinion mounted on the motor shaft. This 50 pinion is intended to coact with a rubber ring *g* bedded in the dished supporting body *h* surrounding the motor of a polishing disc *i*. The supporting body *h* is arranged to rotate about a shaft *k*

which is securely journaled on the machine casing *d* by means of a bow member *m* which embraces the motor casing *a* from below. The bow member *m* at the same time forms a rigid abutment for a helical spring *n* which acts on an extension *o* of the motor casing. This extension is also constructed to form a treadle *p* and is provided at its upper arcuate downwardly sweeping edge with a notch *q*, the object of which is to coact with a pin-like projection *r* of the handle *s* 10 for guiding the machine, more particularly a cross-piece *r* of a bow-shaped extension *t* which is pivoted at either side of the machine casing on pins *t'*.

The drawing shows the machine in its inoperative position, that is with the handle erect. In this position the canting weight of the motor and the spring *n* press the motor extension *o* against the projection *r* of the handle and hold the handle securely in its erect position, so that it is prevented in a reliable manner from sliding off the extension *o*, either should the handle be knocked or more particularly, when the machine for the purpose of placing it aside is grasped by the handle and is thus suspended from the handle 20 25 pivots *t'* with an overbalancing weight on one side.

For putting the machine into operation the handle is brought into its inclined operative position. To effect this it is necessary, in order 30 to bring the handle projection *r* out of the notch *q*, first to move the extension *o* downwards. For facilitating this operation the extension *o* is provided with a plate *p* adapted to be depressed by the foot.

Instead of the spring the canting weight of the motor which is suspended outside its centre of gravity may suffice, so that the spring may be omitted, or, if the motor be suspended in its centre of gravity, the spring alone may be brought into 40 action.

What I claim is:

1. In an electrically driven floor polishing machine in combination, a machine casing, a driving disc rotatable in said casing, a polishing brush connected to said driving disc, a driving motor pivotally mounted on said casing and having a driving shaft with a driving pinion thereon, a spring interposed between the machine casing and the driving motor and arranged to tilt the driving motor to apply the driving pinion to the driving disc, a handle pivotally mounted on the machine casing so as to be capable of being swung from an inclined operative position into an upright inoperative position, a locking projection 50 55

on the driving motor and a co-operating locking projection on the handle arranged to engage the projection on the driving motor and displace the motor against the action of the spring; on the handle being moved into the upright position, and thereby maintain the two projections under spring pressure in engagement with one another.

2. In an electrically driven floor polishing machine, in combination, a machine casing, a driving disc rotatable in said casing, a polishing brush connected to said driving disc, a driving motor pivotally mounted on said casing and having a driving shaft with a driving pinion thereon, a spring interposed between the machine casing and the driving motor and arranged to tilt the driving motor to apply the driving pinion to the driving disc, a handle pivotally mounted on the machine casing so as to be capable of being swung from an inclined operative position into an upright inoperative position, a locking projection on the driving motor and a co-operating locking projection on the handle arranged to engage the projection on the driving motor and displace the motor against the action of the spring, on the handle being moved into the upright position, and thereby maintain the two projections under spring pressure in engagement with one another, the projection on the driving motor comprising a pedal for enabling the driving motor to be dis-

placed against the action of the spring to release the projection on the motor from the projection on the handle.

3. In an electrically driven floor polishing machine, in combination, a machine casing, a driving disc rotatable in said casing, a polishing brush connected to said driving disc, a driving motor pivotally mounted on said casing and having a driving shaft with a driving pinion thereon, a projection on the driving motor on the end thereof remote from the driving pinion, a spring interposed between the machine casing and the driving motor and bearing against said projection so as to tilt the driving motor to apply the driving pinion to the driving disc, a handle pivotally mounted on the machine casing so as to be capable of being swung from an inclined operative position into an upright inoperative position, the projection on the driving motor having a notch therein and the handle having a locking projection thereon arranged to engage the projection on the driving motor and displace the motor against the action of the spring, on the handle being moved into the upright position, and engage with said notch, whereby the handle is secured in the upright position under the pressure of the spring which maintains the locking projection in engagement in said notch.

ERNST FABER.
